UNITED STATES PATENT OFFICE.

ELTON G. BREWER AND CAREY A. CHESHIRE, OF DES MOINES, IOWA.

FEEDER FOR PRINTING-PRESSES.

971,245.

Specification of Letters Patent. Patented Sept. 27, 1910.

Application filed December 2, 1909. Serial No. 530,992.

To all whom it may concern:

Be it known that we, ELTON G. BREWER and CAREY A. CHESHIRE, citizens of the United States, residing at Des Moines, in 5 the county of Polk and State of Iowa, have invented a certain new and useful Feeder for Printing-Presses, of which the following is a specification.

The object of our invention is to provide 10 a feeder for printing presses of simple, durable and inexpensive construction, especially adapted for use in feeding books or pamphlets and so arranged that it may be readily and easily adjusted to fit books or 15 pamphlets of different sizes, and also so arranged that the feeder fingers may be made to firmly engage the lower one only of the pamphlets or books, and said lower one may then be readily and easily moved from under 20 the pile of books contained in the feeding hopper.

Our invention consists in certain details, in the construction, arrangement and combination of the various parts of the device 25 whereby the objects contemplated are attained, as hereinafter more fully set forth, pointed out in our claims and illustrated in the accompanying drawings, in which—

Figure 1 shows a front end elevation of 30 a device embodying our invention. Fig. 2 shows a view of same with the central base plate of the hopper removed. Fig. 3 shows a side elevation of one of the curved base plates and its support. Fig. 4 shows a central, longitudinal, sectional view through a device embodying our invention, and also illustrating the feed and printing rollers of a printing press to show the arrangement 35 of the feeding device relative thereto. Fig. 40 5 shows an enlarged, detail, longitudinal, sectional view of one of the base plates embodying our invention, and Fig. 6 shows a view of a part of a device similar to Fig. 4 with the base plate and the lower book or 45 pamphlet therein in an extended position.

Referring to the accompanying drawings, we have used the reference numeral 10 to indicate that portion of the printing press shown. 11 indicates the printing or type 50 cylinders, and 12, the feed rollers. All of these parts are of the ordinary construction.

Mounted upon the frame is a reciprocating supporting bar 13 capable of movement toward and from the feed rollers. Extended 55 transversely of this bar is a cross head 14. Adjustably mounted on the cross head 14

are two blocks 15 secured to the cross head by the set screws 16. On each of these blocks is a segmental base plate to form the bottom of the hopper for containing the 60 books or pamphlets. Each of these base plates is made vertically adjustable relative to the block 15 by means of the screw-threaded rod 17 which is extended through the block 15 and provided with nuts 18 above and below said block so that each base plate may be independently adjusted vertically and firmly supported in any position of its adjustment. Said base plates may also be adjusted toward and from each other 65 by sliding the blocks 15 on the cross head 14.

At the end of each of the curved base plates is a series of feeding fingers, each of which comprises a straight body portion 19 capable of vertical movement under the base plate and having a feeder point 20 at its upper end. The lower end of each of the body portions 19 is beveled or inclined at 21 and a contractible spring 22 is connected to each of said body portions 19 and tends 70 to hold it downwardly. For the purpose of adjusting the finger relative to the base plate, we have provided a set screw 23 mounted in the base plate and projected to position in engagement with the inclined 75 or beveled portion 21 as clearly shown in Fig. 5. Obviously by moving these set screws inwardly toward the central portion of the base plate, the feeder points 20 are raised, and by withdrawing said set screws 80 the feeder points are lowered.

In order to provide for receiving books or pamphlets of considerable width, we have provided a central, flat top base plate 24 which is mounted on the cross head 14 in 85 the same way as the other base plates before described, and which therefore moves longitudinally in unison with the other base plates. The top portion of this central base plate 24 is preferably made flat as clearly 90 shown in Fig. 1. We have also provided a hopper of ordinary construction for holding the pamphlets contained on the base plates against longitudinal movement with the base plates. This device comprises a 95 series of horizontally arranged rods 25 with vertical rods 26 adjustably connected therewith, said vertical rods being designed to engage the side and end edges of the books or pamphlets contained on the base plates as 100 clearly shown in the drawings. The outer ends of the base plates are preferably pro-

vided with slots 27 to receive the end ones of said vertical rods 26 as clearly shown in Figs. 5 and 1.

In practical use, the books or pamphlets 5 28 to be printed are placed upon the base plates and they obviously will be curved in the manner illustrated in Fig. 1, substantially of the same curvature as the base plates, except that as shown in said figure, 10 the edges only of said books or pamphlets will engage each other and the central portions thereof will stand spaced apart from each other. The rods that form the hopper are adjusted to fit the side and end edges of 15 the books or pamphlets, and the rods at the rear of the hopper adjacent to the feed rollers are so arranged that they will not stand in line with the lower book or pamphlet so that said lower one is free to move rear- 20 wardly in position in engagement with the feed rollers. When the base plates are moved forwardly toward the feed rollers, the fingers 20 will engage the lower book or pamphlet and will carry it together with 25 the base plates toward the feed rollers. As said books or pamphlets enter the feed rollers they will be flattened out so that they will enter between the printing rollers in flat condition for printing.

30 A number of advantages are gained by having the base of the hopper made of seg-mental shape instead of flat—one advan- tage being that the feeder points will more readily enter between the books or pam- 35 phlets on account of the fact that their central portions stand spaced apart, and an- other advantage is that the books or pam- phlets will slide relative to each other more readily because the edges only thereof are 40 in engagement with each other.

We claim as our invention—

1. In a device of the class described, the combination of a reciprocating base plate having its top surface arranged with its 45 sides higher than its central portion so that articles to be printed resting thereon will lie in curved positions with their side edges elevated and so that the lower one of said articles will have its longitudinal central 50 portion spaced apart from the article above

it, a stationary hopper device, and a finger carried by the base plate and designed to enter between the two lower articles at the point where said articles are spaced apart at their longitudinal centers. 55

2. In a device of the class described, the combination of a reciprocating base plate having its top surface curved transversely of its path of travel, to thereby support articles to be printed in such a manner that the longitudinal centers of the lower articles will stand spaced apart, stationary hopper members designed to hold books or pamphlets on the base plates and to permit the lower one thereof to project beyond the base 60 plate, and a finger carried by the recipro- cating base plate to enter between the two lower articles on the base plate. 65

3. In a device of the class described, the combination of two reciprocating base mem- bers curved transversely of their path of travel, means for adjusting them toward and from each other, a central reciprocating base member detachably supported between them, stationary hopper members designed to hold 75 articles on the reciprocating base members, and means carried by said reciprocating members for engaging the lower article thereon.

4. In a device of the class described, the combination of a reciprocating support member, a cross head thereon, two segmental base plates adjustably fixed to said cross head, and feeder fingers at one end of said base plates. 80

5. In a device of the class described, the combination of a base member, a feeder finger mounted therein and capable of up and down movement, and having an inclined lower end, a contractible spring arranged to hold the yielding feeder finger downwardly, and a set screw designed to engage the inclined end, for the purposes stated. 85 90
